BATHTUB ENCLOSURE

William H. Armstrong and Norbert T. Kuypers, Bloomfield Hills, Mich., assignors to Borg-Warner Corporation, Chicago, Ill., a corporation of Delaware

Filed Nov. 21, 1968, Ser. No. 14,567

Term of patent 14 years

Int. Cl. D23—02

U.S. Cl. D23—49

FIG. 1 is a perspective view of a bathtub enclosure showing my new design; and

FIG. 2 is a partial sectional view taken along line 2—2 of FIG. 1.

The broken line representation of a bathtub in FIG. 1 is for purposes of illustration only.

We claim:

The ornamental design for a bathtub enclosure, substantially as shown and described.
